US0D1106367S

(12) United States Design Patent (10) Patent No.: US D1,106,367 S
(45) Date of Patent: * Dec. 16, 2025

(54) TABLE TENNIS RACKET

(71) Applicant: Min Gu Kang, Changwon-si (KR)

(72) Inventor: Min Gu Kang, Changwon-si (KR)

() Term: 15 Years

(21) Appl. No.: 35/522,178

(22) Filed: Sep. 4, 2023

(80) Hague Agreement Data

Int. Filing Date: Sep. 4, 2023

Int. Reg. No.: DM/233300

Int. Reg. Date: Sep. 4, 2023

Int. Reg. Pub. Date: Sep. 6, 2024

(30) Foreign Application Priority Data

Mar. 7, 2023 (KR) 30-2023-0008388

(51) LOC (15) Cl. 21-02

(52) U.S. Cl.

(57)

CLAIM

The ornamental design for a table tennis racket as shown and described.

DESCRIPTION

1. Table tennis racket

1.1 : Perspective

1.2 : Front

1.3 : Back

1.4 : Top

1.5 : Bottom

1.6 : Left

1.7 : Right

1 Claim, 7 Drawing Sheets
